UNITED STATES PATENT OFFICE.

EDWARD V. SCHRANCK AND EDWARD F. KUNKEL, OF MILWAUKEE, WISCONSIN.

HEAT-STORING ATTACHMENT FOR RADIATOR SYSTEMS.

1,338,750.

Specification of Letters Patent. Patented May 4, 1920.

Application filed February 4, 1918. Serial No. 215,408.

To all whom it may concern:

Be it known that we, EDWARD V. SCHRANCK and EDWARD F. KUNKEL, citizens of the United States, residing at Milwaukee, 5 county of Milwaukee and State of Wisconsin, have invented new and useful Improvements in Heat-Storing Attachments for Radiator Systems, of which the following is a specification.

Our invention relates to improvements in heat-storing attachments for the water jackets and radiator systems of motor driven vehicles.

The object of our invention is to provide 15 means for storing up heat when the engine is running and utilizing such stored heat to keep the water in the circulatory system of the motor at a moderate temperature sufficient to prevent freezing.

More particularly, the object is to provide 20 means whereby the heat of the exhaust gases may be absorbed and stored in a storage chamber provided with steatite or any other material capable of absorbing a large number 25 of heat units and allowing slow radiation on account of the slow heat conductivity of the material employed.

In the drawings,—

Figure 1 is a side elevation of an internal 30 combustion motor provided with a water jacket and radiator and also equipped with our improved heat storing apparatus.

Fig. 2 is a detail view, in vertical section, 35 of the heat storing chamber showing its water jacket and circulatory pipe connections.

Like parts are identified by the same reference characters in both views.

1 is the exhaust pipe of an internal 40 combustion engine and 2 is a radiator associated with the water jacket of the engine in the ordinary manner. When used in connection with a motor driven vehicle, the engine is, of course, inclosed within the hood 4.

A chamber 6 is mounted upon the exhaust 45 pipe 1, the bottom of the chamber 6 being preferably concave in form so as to snugly fit over the pipe 1. The chamber is provided with an interior cavity 8 filled with 50 steatite, or what is commonly known as soap stone, this preferably comprising a solid block 9. This cavity 8 may be open at the bottom, whereby the block 9 may be allowed to bear directly on the exhaust pipe, the bottom 55 of the block being hollowed out in concave form to fit the pipe. The chamber 6

also includes a water cavity 11 which is closed, except for a connection 12 with the water jacket of the internal combustion motor and another connection 13 leading to 60 the main hot water pipe connection 15 of the radiator. A third cavity 17, within the chamber 6, is filled with a non-heat conducting material, such as dead air, felt, mineral wool, or any other material adapted 65 to serve as a heat insulator.

It will be understood that, when the engine is running, the stone 9 will absorb heat from the exhaust pipe 1. When the engine stops, a gravity circulation will be maintained 70 through the radiator and the engine jacket, the water thus circulating passing through the cavity 11 and absorbing heat from the steatite 9. As the temperature of the water in the system reduces, heat will be 75 supplied from the steatite block to a sufficient extent to keep the temperature above the freezing point through a considerable period of time. Assuming that the hood is 80 properly jacketed, as would be the case during freezing weather, it is possible to store sufficient heat in the block 9 to keep the water in the system above the freezing point for ten or twelve hours during severe 85 weather and for much longer periods during moderate winter weather.

The heat storing connection is preferably 90 not included as a permanent feature of the circulatory system of the engine, but is adapted for detachable connection therewith by the fittings 12' and 13' by which connection is made with the main line pipe or duct 15, thus allowing the water to pass either through the water heating cavity 11 or through the main line duct 15.

In warm weather, the connections 12 and 13 may be removed and the openings in the fittings 12' and 13' capped. The entire casting, composed of the soap stone 9, water chamber 11, and the outer chamber 17 may 100 be removed.

In cases where the engine is to lie idle in a cold place for a period of time considerably in excess of that in which the steatite is capable of imparting warmth to the water, 105 we may provide an electrical heating unit or plug 22, which may be inserted through the wall of the chamber into the water cavity, or into a socket in the steatite. The heating unit may be connected with a source 110 of electrical energy through wires 23.

We do not wish to limit the scope of our

invention to steatite, as any material capable of absorbing a large number of heat units may be substituted therefor without departing from the invention herein described.

It will be understood that the gravity circulation through the water cavity of my improved attachment will be slow and the heat absorption from the block of steatite will also be slow, since the steatite is not in direct contact with the water. Since the rate of heat loss is reduced in proportion as the temperature of the radiator and engine body approximates that of the surrounding atmosphere, it will readily be understood that the water in the radiator, water jacket and the cavity 11 will be kept above the freezing point for a considerable time, depending largely upon the nature of the weather, and that the warmth imparted to the water by the block of steatite will be transmitted to all parts of the system by the slowly moving currents of water, thus also aiding starting operations of the engine.

25 We claim:—

1. A heat storing attachment for water jacketed internal combustion engines, comprising the combination with said water jacket and connections, of a chamber 30 through which the water may circulate, and a block of steatitic material associated with said chamber and adapted to absorb heat when the engine is in operation and to give up heat to the surrounding water when the 35 engine is at rest.

2. A heat storing attachment for internal combustion engines having a water circulatory system, comprising the combination of a block of heat absorbing material, a water 40 jacket surrounding the block, an inclosing layer of non-heat conducting material, and pipe connections with the circulatory system adapted to allow water to circulate through said water jacket.

45 3. A heat storing attachment for internal combustion engines having a water circulatory system, comprising the combination of a water chamber having detachable inlet

and outlet connections with the circulatory system, a block of material inclosed by said chamber adapted to retain heat obtained from the engine when running, and impart heat to the water when the engine is stopped, and an auxiliary connection around said water chamber, said block and water chamber being made detachable, whereby the same may be removed when desired.

4. The combination of a water jacketed internal combustion engine, of a radiator 60 connected with said water jacket, an auxiliary heat storing chamber provided with a non-heat conducting covering, and means for slowly transmitting heat therefrom to the water in the radiator and engine jacket. 65

5. The combination with a water jacketed internal combustion engine provided with an exhaust pipe, of a radiator connected for water circulation from the water jacket, a block of heat absorbing material 70 mounted on the exhaust pipe, a heat insulating covering therefor, and means for slowly transmitting heat from said block of heat absorbing material to the water in the radiator and engine jacket.

75 6. The combination with a water jacketed internal combustion engine provided with an exhaust pipe, of a radiator connected for water circulation from the water jacket, a block of heat absorbing material mounted 80 on the exhaust pipe, a heat insulating covering therefor, and means for slowly transmitting heat from said block of heat absorbing material to the water in the radiator and engine jacket, comprising a water chamber 85 partially inclosing said block of heat absorbing material, and connections adapted to permit water circulation between said chamber and the radiator.

In testimony whereof we affix our signatures in the presence of two witnesses.

EDWARD V. SCHRANCK.
EDWARD F. KUNKEL.
